UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

TRUCK-EQUALIZING ARRANGEMENT.

1,377,709.

Specification of Letters Patent.

Patented May 10, 1921.

Application filed December 27, 1920. Serial No. 433,417.

To all whom it may concern:

Be it known that I, JOHN A. LAMONT, a citizen of the United States, residing at Chicago, in the county of Cook and State 5 of Illinois, have invented certain new and useful Improvements in Truck-Equalizing Arrangements, of which the following is a specification.

This is an improvement on the load 10 equalizing arrangement disclosed in my co-pending application, Serial No. 433,412, filed December 27, 1920.

One object of the invention is to simplify truck side frames and means for securing 15 thereto equalizing levers in a six-wheel type of truck.

Another object is to provide an improved equalizing truck arrangement whereby co-operative functioning of the parts is im- 20 proved and whereby shocks are taken by the bolster and side frame instead of by the equalizing levers and their connections to the side frame.

These and other objects are accomplished 25 by means of the arrangement disclosed on the accompanying sheet of drawings, in which—

Figure 1 is a fragmentary side elevation 30 of a railway car truck embodying my invention; and,

Fig. 2 is a detail sectional view taken in the plane of line 2—2 of Fig. 1.

The various novel features of the invention will be apparent from the following de- 35 scription and drawings and will be particu- larly pointed out in the appended claims.

Referring to the figures of the drawings, it will be noted that I have disclosed my invention in connection with a six-wheel 40 truck having a side frame 10 with end journal box openings 11 and a middle journal box opening 12, and bolster openings 13 intermediate said journal box openings for the reception of the four legs of a bolster.

45 Mounted in each of the bolster openings 13 is a bolster or bolster member 14 which has a slight amount of clearance with respect to the side frame and is movable vertically therein and rests upon an intermediate portion of an equalizing lever 15, one end of which is operatively connected with the equalizing mechanism associated with

the intermediate journal box 16. The opposite end of each equalizing lever turns upwardly and is provided with a seat 17 which receives the lower rod 18 of a closed or looped hanger 19, the upper end of which is provided with an eye portion 20 for pivotally receiving a pin 21 extending between side walls 22 and 23 of the side frame 10. 60

By means of this connection between the side frame and the equalizing levers the side frame itself is simplified, especially from the production point of view, and it also permits the lowering of the outer end 65 of each equalizing lever and provides an increased amount of clearance between the inner ends of the equalizing levers and the springs associated with the intermediate journal box. Furthermore, by having the 70 equalizing levers suspended on the hangers 19 from the side frame 10 the equalizing levers are permitted to swing a limited amount lengthwise of the truck, so that the force of shocks occasioned by bringing 75 the car to rest or starting same is transmitted through the bolsters to the sides of the bolster pockets in the frame, instead of direct to the hangers or hanger pins. In this manner the life of the parts is in- 80 creased and the design simplified.

It is my intention to cover all modifications of the invention falling within the spirit and scope of the following claims.

I claim:

1. In a railway car truck, the combination of a side frame having a bolster opening, an equalizing lever, a bolster mounted within said opening and mounted directly on said equalizing lever, and a hanger pivoted to said side frame and supporting said equalizing lever whereby the latter may have a lengthwise movement with respect to the side frame and whereby thrusts are taken directly by the bolster and said frame. 90

2. In a railway car truck, the combination of a side frame having a bolster opening, an equalizing lever mounted therebelow, a bolster movably mounted in said bolster opening and directly carried by said 100 equalizing lever, and a hanger pivoted to said side frame and supporting one end of said equalizing lever whereby said equalizing lever may move lengthwise with respect

to the side frame permitting shocks to be absorbed by the bolster and side frame.

3. In a railway car truck, the combination of a support, a bolster associated with said support, an equalizing lever for directly carrying said bolster, and a hanger connected to said support and to said

equalizing lever whereby lengthwise directed operating shocks may be absorbed by said support and bolster.

Signed at Chicago, Illinois, this 15th day of December, 1920.

JOHN A. LAMONT.
